ROTARY-TYPE BURNER FOR SOLID FUELS

Weston M. Fulton, Knoxville, Tenn.; Barbara S. Fulton, John H. Murrian, and Robert W. Fulton, executors of said Weston M. Fulton, deceased, assignors to W. J. Savage Company, Knoxville, Tenn., a corporation of Tennessee

Application July 27, 1944, Serial No. 546,771

19 Claims. (Cl. 110—35)

1

This invention relates to improvements in burners for solid fuels, particularly of the general type set forth in my prior copending applications, Serial No. 529,501, filed April 4, 1944, Rotary burner, now Patent No. 2,395,733, granted February 26, 1946; Serial No. 529,502, filed April 4, 1944, Fuel burners for boilers; Serial No. 529,503, filed April 4, 1944, Fuel burners, now Patent No. 2,444,985, granted July 13, 1948; and Serial No. 535,848, filed May 16, 1944, Burners for solid fuels, now Patent No. 2,427,596, granted September 16, 1947.

It has been proposed heretofore, to utilize revolving grates of different types for the burning of solid fuel, the grates being caused to rotate within a cylindrical enclosure. One form thereof has provision for rotating both the grates and the enclosing drum, while another form rotates the grates while the enclosing drum remains stationary. In still another application of this principle, the grates are rotated intermittently at intervals and the enclosing drum remains stationary at all times.

In all of such prior devices, the grates while being enclosed within a drum or cylinder, are spaced away from the interior wall of the drum so that there is no appreciable contact between the interior cylindrical wall of the enclosure and the grates themselves. I have found that this makes them objectionable because the grates cannot dissipate heat to and through the walls of the enclosure with sufficient speed to prevent the grates from being heated to a temperature sufficiently high to cause ashes and clinkers to fuse upon the grates and adhere thereto. I have found also that it is necessary to maintain the temperature of the surface on which combustion takes place below the temperature of fusion of the ashes formed from the fuel being burned in order to prevent this objectionable condition.

One of the objects of this invention is to provide for holding the rotating grates in firm contact with the inner wall of the enclosing drum or other cooling surface, so that the grates cannot become heated sufficiently to permit clinkers to adhere thereto.

It is well-known to combustion engineers that solid fuels may be classed as agitating, semi-agitating and non-agitating. I have observed from varied and lengthy tests that during the process of combustion, some fuels, such for example, as bituminous coal, change from agitating to semi-agitating at successive stages of combustion. For example, when the coal is first fed into a rotating burner, it may be of the agitat-

2

ing type and hence require considerable agitation as it begins to burn. As combustion proceeds to the point where most, if not all, of the volatile content of the coal has been distilled off and burned, the remaining carbonaceous material comes within the class of semi-agitating fuel, and therefore, must be agitated to a lesser degree than the fuel introduced into the burner. Finally, it may reach the condition of non-agitating fuel and hence should not be agitated appreciably.

A further object of this invention is to provide different parts in a burner for rotation at speeds differing from each other, according to the different conditions of the fuel passing therethrough, and one part may be held stationary, if desired, to permit the combustion of the fuel when it reaches the non-agitating stage.

When rotating grates firmly contact the stationary inner wall of the enclosing drum, a substantial amount of friction results which resists the rotation of the grates to such an extent that a substantial amount of power is required for rotating the grates.

Yet another object of this invention is to reduce to a minimum the friction incident to the rotating grates and render most effective the rotating power applied thereto, by an application of power with substantially equal force at two opposing points substantially diametrically on opposite sides of the center of the rotating grates around the periphery thereof.

In my experiments with rotary burners, I have found that radiant heat given off from the incandescent fuel in such a rotary burner, has a tendency to pre-ignite the incoming fuel and thus cause "burning back" into the fuel supply hopper. I have provided a means as set forth in my Patent No. 2,444,985, mentioned above, for preventing the occurrence of such "burning back."

Still another object of this invention is to provide a further safeguard against this eventuality, by injecting a limited amount of cool air into the fuel inlet opening of the rotary burner.

I have shown a preferred embodiment of my invention, together with a modification thereof, in the accompanying drawings, in which:

Fig. 1 is a side elevation of the rotary burner applied to a furnace, with parts broken away and in section for clearness of illustration;

Fig. 2 is an end elevation of the burner thereof;

Fig. 3 is a longitudinal section through the burner substantially on the line 3—3 of Fig. 2;

Fig. 4 is a vertical cross-section through the burner on the line 4—4 of Fig. 3;

Fig. 5 is a perspective view of a portion of the grate structure with parts broken away and in section to clarify the illustration;

Fig. 6 is a side elevation of one of the grate bars detached;

Fig. 7 is an end elevation thereof;

Fig. 8 is a side view of one of the grate supporting ratchet wheels detached;

Fig. 9 is an edge view thereof; and

Fig. 10 is a diagrammatic plan view of a rotary burner showing a modified form of driving mechanism for the grate structure.

In the form of the invention illustrated in the drawings, the burner comprises two main parts designated respectively at 1 and 2, each of which is constructed substantially of annular form and mounted in stationary position against rotation. The parts 1 and 2, being elongated horizontally, form an enclosed hollow non-rotating shell extending about the rotating grates mounted therein.

The burner part 1 is formed with an outer wall 3 (see Figs. 3 and 4), an inner wall 4 and end walls 5 and 6, enclosing therebetween an annular space or water chamber 7. This annular space 7 is adapted to be filled with water or other cooling medium which may be supplied thereto by convectional circulation from the boiler to which the burner is attached in a manner similar to that described in my prior application on Fuel burners for boilers, Serial No. 529,502, filed April 4, 1944, as hereinafter referred to more in detail.

In a similar manner, the part 2 has an outer wall 8, an inner wall 9, and end walls 10 and 11, enclosing an annular space 12 which is adapted to be filled with water in the same manner and from the same source as described above in connection with the burner part 1.

While the burner parts 1 and 2, each may be made in a single piece, I prefer to construct each of them in a plurality of sections, generally in the manner well-known in the manufacture of cast iron heating boilers, for the purpose of simplifying and reducing the cost of manufacture in production. The part 1 (see Fig. 1) is shown as composed of end sections 13 and 14 and a plurality of intermediate sections 15. Each of these sections is provided with inlet openings at its bottom and outlet openings at its top. These openings are connected together by means of push nipples 16 (Fig. 3) which form a water-tight joint with the sections around their outer circumferences but permit the free flow of water through their hollow interiors between the sections. This permits an open water course through the space 7 formed in the part 1. The burner part 2 is likewise formed of separate sections 17 similarly constructed and connected together through nipples 16', which form an open passageway therethrough in the space 12.

Each of the intermediate sections 15 has the water space 7 therein narrowed in width throughout a part of its circumference so that when the sections are assembled together, as shown in Fig. 3, air chambers 18 are formed between the sections at the narrowed portions. These air chambers 18 are enclosed at opposite sides by walls 19 integral with the sections, formed as ribs therein, and closed at the circumference of the sections by the outer wall 3. At each opposite edge of each section 15, the wall 3 has a gap therein which cooperates with a similar gap in

an adjacent section to form a slot 20 into the periphery of each air chamber 18 through which air can be blown into this chamber for discharge into the burner. As shown in Fig. 3, the slots 20 are of different widths, being largest at the intake end of the burner and smallest at its outlet end. This arrangement serves to admit the largest volume of air at the end of the burner where fresh fuel is being introduced, and the smallest amount at the end where ashes are being formed and discharged, the volume of admitted air decreasing progressively from the inlet end to the discharge end.

Each of the sections 17 of the burner part 2 is likewise narrowed along a part of its circumference so that when these sections 17 are assembled together, an air chamber 22 is formed in the sections enclosed at opposite sides by ribs 23 and at its periphery by the outer wall 8 of the burner part 2. The outer wall has gaps in the portions thereof provided for the respective sections that are spaced apart to form a slot 24 into the periphery of the air chamber 22, through which air is blown into this chamber, thence into the burner, as indicated by the arrows in Fig. 3. This slot 24, corresponding with the slots 20 in the burner part 1, is of smaller width than the latter slots so as to admit a smaller amount of air for the purpose described above.

Mounted on one side and near the bottom of the burner, as shown in Figs. 1 to 4, is a wind-box 25 which extends throughout the major portion of the length of the burner, including the parts 1 and 2, enclosing therein the slots 20 and 24, as will be evident from Figs. 1 and 3. The wind-box 25 is adapted to supply air to these slots, as indicated by the arrows in Figs. 3 and 4. An air duct 26 extends to the wind-box 25 from a blower 27 for supplying air, as needed, to the wind-box, which in turn directs it into the burner, as described.

At the interior of the burner part 1 is a series of grate-bars 28 (Figs. 4 to 7), the exact construction of which is shown more clearly in Figs. 5 and 6. Each of the grate-bars is formed of slightly arcuate shape in cross-section, as shown in Figs. 3, 4 and 7, and has beveled opposite edges 29. Each grate-bar also has reduced opposite ends 30.

The grate-bars 28 are mounted in and moved by driving rings 31, 32 (see Figs. 5, 8 and 9). These rings 31, 32 are exact duplicates except that they are respectively of "right" and "left" design, intended to be in opposed cooperating relation. Each ring is provided with an integral inwardly projecting rim 33 at its inner edge, and formed with notches 34 therein leaving projections 35 between the notches which engage loosely with the reduced ends 30 of the grate-bars 28 that are mounted in the notches 34. Each of the projecting ends 30 of the grate-bars is formed substantially of "keystone" shape, and the notches 34 are similarly shaped but of slightly larger size so as to receive the ends 30 loosely, although confining the grate-bars against dropping through the inner sides of the rings 31, 32 for retaining them in place.

The rings 31, 32 are mounted to rotate freely within opposite ends of the burner part 1, which serve as bearings therefor, there being sufficient play provided between the rings and the bearings to allow for expansion and contraction resulting from wide changes in temperature. The reduced ends 30 of the grate-bars 28 set sufficiently loosely

in the notches 34 to permit the grate-bars to have substantial movement towards and away from the axis of rotation of the rings 31, 32, although as pointed out above, this movement is restricted to prevent the ends 30 from becoming disengaged by the projections 35 by which the grate-bars are moved, as will be evident from Figs. 4 and 5. Furthermore, these parts are so proportioned that the grate-bars are spaced in relation to each other so as to leave longitudinal slots or openings 36 therebetween, formed by the adjacent beveled edges 29 of the grate-bars which are so disposed as to provide substantially a tangential arrangement of the openings 36 relative to the interior of the burner, as shown in Fig. 4.

Each of the driving rings 31, 32 has on its peripheral portion thereof, ratchet teeth 37 in this form of the invention, as a means of driving the rings and thereby the grate-bars, as hereinafter described. The ratchet teeth on both of the driving rings 31, 32, of course, are of the same pitch.

The burner part 2 is provided with a driving ring 39 which is similar to the rings 31 and 32, except that it extends continuously throughout the width of the burner part 2 and has an inwardly disposed annular rib 40 at the inner end of the burner. Furthermore, the driving ring 39 has ratchet teeth 41 on its peripheral rim portion but of shorter pitch than the ratchet teeth 37 so as to provide for finer stepping adjustment of the driving ring 39 than of the driving rings 31, 32.

The driving ring 39 has rectangular openings 42 arranged at intervals around its circumference and loosely receiving therein, grate-bars 43. These openings and grate-bars taper inwardly, as shown in Fig. 5. Each grate-bar is sufficiently smaller than its co-acting opening so as to provide longitudinal spaces or slots between an edge of the grate-bar and the adjacent edge of its opening 42, as indicated at 44 in Fig. 5. These openings or slots 44 are likewise disposed generally in a tangential direction relative to the cylindrical wall of the burner. The loose fit of the grate-bars 43 in the openings 42, permits the grate-bars to have substantial movement toward and away from the axis of rotation of the ring 39. One purpose of this, is to allow for expansion and contraction between the grate-bars and their openings, due to wide changes in temperature, often unevenly distributed between the bars and the openings. Another purpose, is to provide the spaces 44 through which air can pass into the discharge end of the burner to support combustion, as indicated by the arrows in Fig. 3.

At the fuel inlet end of the burner is a stationary burner head 45 (Fig. 3), which forms an enclosure for the cylindrical burner structure. The burner head 45 is hollow to provide a water space 46 therein, and having inlet and outlet water connections at its bottom and top respectively, each of which is provided with a push nipple, one being shown at 48 at the top, as a means of connecting the burner head with the burner part 1. These connections permit free circulation of water between the water chamber 46 in the burner head and the water chambers 7 and 12 in the burner parts 1 and 2 in a manner usually employed in the construction of cast iron boilers.

One end of the cylindrical burner is supported by means of the burner head 45, which is carried by legs 49 on a base 50, preferably bolted thereto. The opposite end of the burner may be supported in any convenient manner, but I prefer that it be

seated in a fire-brick wall 51 (Fig. 1) which connects the outlet end of the burner with a heating boiler 52. The fire-brick wall 51 has a chamber 53 therein, receiving the products of combustion from the burner and having a fire-brick face in opposed relation to the open end of the burner, generally as described in connection with my prior application, Serial No. 529,502.

When all of the sections of the burner parts 10 1 and 2 are assembled together with the burner head 45, they constitute an integral non-rotating enclosure for the rotating grates. One end of this enclosure is connected with the furnace structure including the fire-brick wall on which 15 the enclosure is mounted. Hence, it is only necessary to support separately the opposite end of the structure. It is not required that the respective sections be supported intermediate their ends since these two points of support at the 20 respective opposite ends, will be sufficient.

The burner head 45 is provided also with the fuel inlet 54 opening into the inner side of the burner at a point preferably located at the vertical longitudinal plane through the axis of the 25 burner, and preferably above the axis. This fuel inlet is preferably in the form of a zigzag conduit through which the fuel may be directed into the outer end of the burner from a suitable source of fuel supply, such as a hopper, as described in 30 my prior application, Serial No. 529,502.

Referring to Figs. 1 and 2, the rotor of the blower 27 is keyed on the armature shaft 55 of an electric motor 56, which is attached to the base 50 by means of bolts 57. This motor 56 35 also drives the operating parts of the burner.

The opposite end of the armature shaft 55 has a pulley 58 keyed thereon and connected by a V-belt 59 with a pulley 60, which is keyed to the drive shaft 61 of a speed reducer 62 that is 40 mounted on the base 50 adjacent the motor 56.

The speed reducer 62 has a reduced speed power output shaft 63 on which is mounted a crank 64 for turning movement thereby. A link-arm 65 has one end pivoted to the crank 64 and its opposite end pivotally connected with the lower end of a swinging lever-arm 66. The lower end of the lever-arm 66 is bifurcated to receive 45 therein the adjacent end of the link-arm 65.

As a means for supporting the lever-arm 66, 50 the burner head 45 has integral therewith, a shelf 67 on which is supported a knife-edge pivot block 68 held in position by a screw 69 and adjustable transversely of the shelf 67 by a screw 70, which is threaded through an upstanding portion of the shelf. Opposite from the shelf 67 is a knife-edge pivot member 71 integral with the burner head 45. The lever-arm 66 has V-cavities 72 in opposite sides of its upper end which receive the knife-edge pivot members 68 and 71 thereby forming a frictionless knife-edge bearing about which the lever-arm 66 can 55 oscillate freely.

I prefer this type of bearing for the lever-arm 66 because it does not require lubrication. The 60 heat from the burner head 45 conducted through a bearing support connected thereto, would render the lubrication satisfactorily of a pin-pivot or journal bearing difficult. Any of the pin-pivots of the oscillating parts of the mechanism, 65 may be replaced by knife-edge pivots, similar to 70 that here described, if desired.

The lever-arm 66 is also bifurcated at its middle portion, as shown at 73 in Fig. 1, thereby providing an open space in which is located a walking beam 74, pivoted at 75 intermediate its ends to

the lever-arm 66. The opposite ends of the walking beam member 74, carry links 76 and 77 pivoted thereto. These links 76 and 77 extend transversely of the burner head 45 in opposite directions, and have their outer ends pivotally connected at 78, 79, respectively, with crank-arms 80, 81, keyed to shafts 82, 83 journaled to turn freely in bearings 84, 85, respectively, integral with the burner part 1. Also keyed to the shafts 82, 83 are short crank-arms 86, 87, two crank-arms being provided on each shaft, which crank-arms carry pawls 88, 89, held in engagement with the teeth 37 of the driving rings 31, 32 by means of springs 90, 91. On the outer ends of the shafts 82, 83, are keyed crank-arms 92, 93, which carry pawls 94, 95, held in operating engagement with the teeth 41 of the driving ring 39 by means of springs 96, 97. Crank-arms 92, 93 are shorter than the crank-arms 86, 87, so as to provide for smaller throw of the pawls 94, 95 than of the pawls 88, 89, consistant with the smaller size of the teeth 41 than the teeth 37. The crank-arms 80, 81, as well as the crank-arms 86, 87 and 92, 93, are respectively of equal length at opposite sides of the burner. This insures the application of equal force at substantially diametrically opposite points on the driving rings 31, 32 and 39.

The two bearings 84, 85 nearest the inlet end of the burner are provided with brackets 98, 99, in which are threaded set screws 100, 101 in the path of swinging movement of the crank-arms 86, 87, for limiting the extent of movement of these crank-arms in one direction. This would likewise limit the movement of the arms 92, 93, which are keyed to the same shafts 82, 83.

A pipe 102 connects the housing of the blower 27 with the fuel inlet 54, having a nozzle 102' directed along the central axis of the lower pipe section so that air discharged therefrom will be directed downward through the inlet 54 into the interior of the burner. Thus, when the blower 27 is operated to supply air through the duct 26 into the wind-box 25, and thence through the slots 20 and the grate-bar openings 36 and 44 into the fuel bed inside the burner, air will be supplied also through the nozzle 102' in the fuel inlet 54.

One or more inlet connections are provided at 103 in the stationary burner grate enclosure (Fig. 2), and similar outlet connections 104, leading respectively to the bottom and top portions of the steam or hot water boiler 52. Thus water from the bottom of the boiler will be directed into the water passages of the burner enclosure through the connection 103 where it will be heated and returned to the boiler through the top connection 104, as described more in detail in my co-pending application, Serial No. 529,502.

Referring to Figs. 3 and 4, the burner head 45 has integral therewith, a hollow member 105 which is in open communication with the chamber 46 of the burner head so that water can circulate freely therebetween. The member 105 extends throughout the entire length of the interior of the burner, as shown in Fig. 3, and is crescent-shaped in cross-section, as shown in Fig. 4. This member 105 is spaced from the interior wall 4 of the grate enclosure to permit the grates 28 and 43 to slide freely through the space between the wall 4 and the member 105. The member 105 preferably is not concentric with the wall 4 of the grate enclosure, the eccentricity being sufficient to make the space between the

two increase somewhat as the grates pass around in the direction of the arrow in Fig. 4.

The member 105 has integral with its terminal edges, two channels 106 extending lengthwise thereof, and have channels 107 at opposite ends thereof, in which channels 106, 107 rest the edges of a fire-clay baffle 108. The purpose of this baffle is similar to that described in my Patent No. 2,427,596, for Burners for solid fuels. The baffle 108 is preferably spaced somewhat from the member 105, as indicated at 109 to reduce the heat exchange therebetween.

The member 105, forming a water cooled baffle, used alone or in connection with the refractory baffle 108, is claimed in a copending application of Weston M. Fulton and Sidney R. Galyon for Rotary grate burners, Ser. No. 546,770, filed July 27, 1944, now Patent No. 2,426,348, granted August 26, 1947.

Referring to Figs. 3 and 5, the driving rings 31, 32 have recesses 110, 111 into which are placed flexible expanding packing rings 112, 113. These rings are collapsed slightly before being put into place, and their resilience causes them to tend to expand circumferentially. The outer edge of each of the recesses 110, 111 is beveled at the point where the packing rings 112, 113 press. This pressure produces a wedging action which tends to cause the ring 112 to press the driving ring 31 to the right in Figs. 3 and 5, thereby maintaining a tight joint between the driving ring 31 and the end wall 5 of the burner part 1. In like manner, the packing ring 113 tends to force the driving rings 32, 39 apart causing them to make tight joints respectively with the end wall 6 of the burner part 1, and with the end wall 10 of the burner part 2. Also the packing ring 113 seals the joint between the driving rings 32, 39.

In order to safeguard further against the possible escape of very fine ashes from these joints, I have provided flanges 117, 118 (Figs. 1 and 3) integral with the burner parts 1 and 2 respectively, which flanges enclose the driving rings 32, 39 throughout the lower half of their circumference, thereby forming a catch basin 119, into which any escaping ashes may fall. Likewise, flanges are formed on the burner part 1 and burner head 45 to enclose catch basin 120 extending about the lower circumference of the driving ring 31 for any particles that may escape about this ring.

These catch basins terminate at their bottoms in pockets 121, 122, respectively (Fig. 1), which are connected together by a conveyor pipe 123, carrying a small conveyor screw 124. The pipe 123 also includes short sections that extend from the pockets to the ends of the burner. The screw 124 is driven by a ratchet wheel 125 on the shaft thereof, and engaged by a pawl pivoted in the bifurcation of an oscillating arm 126 journaled on the screw shaft, and which is moved back and forth by means of a pin 127 projecting from a side of the swinging lever-arm 66. Thus the screw 124 will be operated upon the operation of the mechanism of the burner, whereby any slight particles caught in the pockets 121, 122, are conveyed to the open end of the pipe 123 and there discharged into the ash-pit or other ash disposal means, along with the ashes from the burner, at the bottom of the chamber 53, as shown in Fig. 1.

Operation

In the operation of the burner, fuel is fed through the inlet 54 by any suitable means, preferably mechanical stoker mechanism of the character set forth in my prior application, Serial No. 529,502. In the meantime, the motor 56 drives the speed reducer 62 and through the crank 64 and link-arm 65 causes the swinging lever-arm 66 to oscillate back and forth from right to left, as viewed in Fig. 2, carrying with it the walking beam member 74. This oscillating movement of the lever-arm 66 will cause oscillation of the crank arms 80, 81 and stepping movement of the pawls 88, 89 and 94, 95, acting respectively on the teeth 37 and 41 to rotate the driving rings 31, 32 and 39 in the direction indicated by the arrow in Fig. 5.

Since the crank arms 92, 93 are shorter than the arms 86, 87, the pawls 94, 95 will move through a shorter distance than the pawls 88, 89. The teeth 41 of the driving ring 39 are made shorter than the teeth 37 to correspond with the shorter movement of their driving pawls. Therefore, it is evident that the ring 39 will be driven at a slower rate than the rings 31, 32. By selecting the proper lengths for the crank arms, it is evident that any desired difference in speed of rotation can be obtained for the driving rings.

Since the walking beam member 74 is pivoted midway of its opposite ends, force will be applied equally by the driving pawls which are located at substantially diametrically opposite points on the circumference of the driving rings. This is important for practical results, because if the driving force is not applied equally in this manner, these driving rings 31, 32 and 39 would offer undue resistance to the driving force.

As the rings 31, 32 are thus caused to rotate in the direction indicated by the arrows in the drawings, they carry with them the grate-bars 28 alone with the burning fuel that lies on these grate-bars. As pointed out above, the opposite edges of the projections 35 are disposed at an acute angle relative to the radius of the driving rings. Likewise, the opposite edges of the reduced ends 30 of the grate-bars are shaped at corresponding angles of a keystone. Therefore, when the driving force is applied in a direction tangent to the circle of rotation, there is a resultant component of force tending to push the bars outward from the axis of rotation. Hence these bars being free to move outward, are urged by their own weight, plus the weight of superimposed fuel, plus the component of force mentioned, to bear against the inner wall 4 of the water-cooled enclosure. In this manner, they are maintained in firm contact with this cooled surface throughout their entire length while they are passing through the region covered by the major portion of the fuel bed, as indicated at B in Fig. 4, in the lower segment of the burner. It is in this region that the grate-bars are subjected to the most intense heat, and therefore, require the maximum degree of protection.

As the grate-bars 28 are carried forward in the direction indicated by the arrows, they enter the space between the water-cooled member 105 and the outer enclosure. As the bars approach the region vertically above the center of rotation, they are free to drop down by gravity onto the peripheral surface of the member 105. Here it will be noted that the action of gravity gradually shifts the grate-bars away from the water-cooled enclosure towards the member 105. Also

the bars are relieved of the weight of fuel as they rise above the fuel bed, and hence the driving force is reduced to a minimum, the component of force tending to deflect the grate-bars outwardly is likewise reduced. Consequently, the bars, upon entering the space between the member 105 and the water-cooled enclosure, soon drop of their own weight down onto the periphery of the member 105 and bear thereon in their movement over the upper portion of said member. These bars are then carried around on this member to where they emerge from the space mentioned, and in so doing, reach a region where all of the forces previously mentioned begin to come into play, and thus force the bars outwardly against the enclosure wall 4.

It will be noted that the construction and arrangement of the grate-bars and their driving mechanism, as described, cause these grate-bars to be held in contact with the surrounding cooling surface by yielding forces, i. e., gravity and mechanical power transmitted through two slidably connected surfaces. It is necessary that these forces be yielding, as opposed to rigid means, in order to provide for the expansion and contraction of the grates and other parts, due to wide variations in temperature, and also to be self-adjusting for wear.

Since the curvature of the member 105 is eccentric to that of the enclosure wall, the space therebetween increases from the point where the grates enter this space to the point where they leave it. The object of this arrangement is to prevent any possibility of the grates becoming clogged by any foreign matter which may accidentally exist in the fuel, and which may adhere to the bars and be carried by them into this space. It will be evident from Fig. 4 that any particles small enough to be carried by the grates through the restricted entrance to this passage, would be carried progressively along to constantly increased freedom of movement so that it could not clog the grates.

The increased size of this grate passage from its entrance to its exit also permits the grates to change their relative relationships moving in a non-circular orbit, and thus free the air spaces 36 between them from small pieces of fuel which may drop therein. It is evident that as each forward moving grate-bar drops down onto the member 105, the space between it and the next adjacent grate-bar, is enlarged somewhat, thus freeing all particles contained in this space. Furthermore, as the grate-bars move to the exit side of this space, they again change relationships, and finally their relationship is changed for a third time as they move into and through the fuel bed B, as shown in Fig. 4. This constant shifting action makes the grate-bars self-cleaning and has proven from practical tests of the construction to possess great merit.

As fuel is fed into the burner at the fuel inlet 54, it drops onto the grates or lower edge portion of the fuel bed and is carried around by the grate-bars through the fuel bed. It is there supplied with air from the wind-box 25 through the slots 29 and air chambers 18, thence through the openings or slots 36 between the grates into the bed of burning fuel, as indicated by the arrows in Figs. 3 and 4. Since the slots 29 gradually decrease in size toward the discharge end of the burner, the amount of air admitted to the fuel will be decreased correspondingly at successive points. When fuel first enters the burner, it gives up its volatile content at the fast-

est rate, and hence a large volume of air is required to burn these volatile gases in addition to the amount required to burn the fixed carbon. Obviously, this demand for air gradually decreases as the fuel is shifted toward the outlet end of the burner.

As pointed out above, many fuels which are properly classed as "agitating fuels" become "semi-agitating fuels" as combustion proceeds. The burner part 2 will take care of this eventuality. As the fuel moves through the burner from the inlet to the outlet end thereof, it leaves the burner part 1 and enters the burner part 2. Since the burner part 2 is driven at a slower speed of rotation than the burner part 1, the degree of agitation is reduced accordingly. Here the grate-bars 43, being free to move about in the openings 42, shift in the same manner as the grate-bars 28 with respect to the burner part 1, thus possessing the same self-cleaning and other advantageous features described above. Since the fuel steadily decreases in volume as it passes through the burner due to its consumption by combustion, the burner part 2 is not ordinarily required to have the same volumetric capacity as the burner part 1, and hence its length may be appreciably less than the burner part 1.

I have found by experience that a limited amount of air blown downward through the fuel feed inlet 54 by the nozzle 102', aids the cooling of this entrance and also reduces the intensity of radiant heat emitted upward through this entrance from the burning fuel in the burner. Since air is highly diathermic, the air itself probably does not intercept any large portion of the radiant heat. However, it is my opinion that very fine particles of fuel which would otherwise loiter by flotation in this fuel inlet passageway are caught by this stream of incoming air and carried quickly into the combustion chamber, whereby, they are prevented from absorbing an excessive amount of radiant heat, and becoming pre-ignited therefrom. Evidently, all of the heat which is absorbed by these fine particles is quickly carried by them, back into the combustion chamber by the air injected in the fuel inlet by the air jet 102'. It is also my opinion that these fine particles, which constitute the very substantial part of most commercial grades of coal, and which are highly athermanous, do intercept a very substantial percentage of the radiant heat emitted from the combustion chamber. Since this air jet 102' prevents these particles from loitering enroute to the burner, they are not allowed to collect heat. Furthermore, this air jet impinges against the surface of the burning fuel at the very point from which heat is emitted into the fuel passage. This incoming air being relatively much cooler than the burning fuel reduces the temperature of the latter at its immediate radiating surface, and thereby reduces the intensity of radiation in proportion.

It will be evident from the foregoing that this improved burner construction accomplishes the several desired results pointed out, and is a material improvement in burners that utilize revolving grates.

It will be understood also that the drawings are intended to be merely illustrative of the principal embodiment of the invention, and that changes in mechanical forms may be made without departing from my invention. For instance, while I have shown only two main burner parts, any desired number of parts may be used, operated at different rates of speed from each other. Fur-

thermore, one of the burner parts, at the outlet end of the burner, may be non-rotating in the manner described in my Patent No. 2,427,596. In this event, the flanged portion 40 of the ring 39 would be replaced by a helical edge of the type described in my said application. This would enable me to utilize fuel which passes successively through stages from "agitating" to semi-agitating" and then to "non-agitating."

It is also evident, that while this burner construction is shown as applied to the heating of steam or hot water, it may be used as well for other types of furnaces, such as hot air furnaces. In this event, air instead of water is circulated through the passageways of the enclosure, which may be provided somewhat larger and more spacious for this purpose than is necessary for water passages. Such air circulation may be accomplished in any of the ways set forth in my aforesaid corresponding patents, No. 2,395,733 and No. 2,444,935.

The fire-clay baffle 108 is similar to the corresponding baffle set forth and claimed in my application, Serial No. 535,848, being used for a similar purpose. Here the baffle has an additional advantage, however, of protecting the grates from the burning fuel. The water-cooled member 105 affords added protection for the grates and also furnishes a relatively cool surface for them to rest upon while moving through the upper portion of their path of rotation. While either of these members 105 or 108 may be used alone without the other, in some installations, especially where other means are available to prevent pre-cooling of the gaseous products of combustion, I prefer to use both baffles for general purposes.

While I have shown, and prefer to employ, the arrangement set forth above for insuring uniformly distributed power at two diametrically opposite points on the driving rings, I may employ other mechanical means for this purpose, if desired. Another example thereof is shown in Fig. 10, in which a rotating burner part is shown at 141, provided with driving rings 142, 143, which driving rings have gear teeth provided at their peripheries, instead of the ratchet teeth referred to above. Also, these driving rings are rotated by pinions 144, 145 mounted respectively on shafts 146, 147. These shafts are mounted at diametrically opposite sides of the burner part 141 so as to apply equal driving forces to the driving rings and on opposite sides thereof.

The shafts 146, 147 may be driven in any suitable manner, but for purpose of illustration, I have shown them operated by worm gear speed reducers 128, 129, which in turn are operated by cross-stub shafts 130, 131 from a differential 132. The differential 132 is operated by a drive shaft 133, carrying a driving gear 134, which may be operated by a pinion 135 mounted on the armature shaft of an electric motor. This form of driving mechanism also obtains an equalization of power in the driving of the burner part or parts, generally with the results pointed out above.

I claim:

1. In a burner of the character described, the combination of an annular structure extending about an approximately horizontal axis and including an inner surface and having means for circulating a cooling medium in heat exchange relation with said inner surface, rotary grates extending lengthwise of the axis of said annular structure throughout the major portion of the length thereof and mounted for movement

through an orbit for supporting the fuel bed on the grates in the lower portion of the orbit, and means for turning said grates in bearing relation with said inner surface.

2. In a burner of the character described, the combination of an enclosing structure having an annular inner surface with means for circulating a cooling medium in heat exchange relation with said inner surface, rotary grates, and means for rotating said grates in yieldable bearing relation with said inner surface.

3. In a burner of the character described, the combination of an enclosing structure extending about an approximately horizontal axis and including an inner wall surface and means for confining a heat exchange medium in heat exchange relation with the periphery of the wall surface for cooling said surface by dissipating heat therefrom, grates mounted in peripheral bearing relation against said inner wall surface and extending lengthwise of the axis of said inner wall surface throughout the major portion of the length thereof and movable in an orbit for supporting the fuel bed on the grates in the lower portion of the orbit, and means for rotating said grates.

4. In a burner of the character described, the combination of an enclosing structure including an inner wall surface and means for confining a heat exchange medium in heat exchange relation with the periphery of the wall surface for cooling said surface by dissipating heat therefrom, grates mounted for peripheral bearing relation with said inner wall surface and for inward yielding movement relative thereto, and means for rotating said grates while in bearing relation against said wall surface.

5. In a burner of the character described, the combination of a tubular burner structure mounted approximately on a horizontal axis and including an inner wall surface and means for confining a heat exchange medium in peripheral bearing relation with said wall surface for dissipating heat therefrom, cylindrical grate structures having side surfaces thereof mounted on peripheral bearing relation against said inner wall surface, said grate structures extending lengthwise of the inner wall surface throughout the major portion of the length thereof and movable through an orbit in bearing relation therewith for supporting a fuel bed on the grate structures in the lower portion of the orbit, and means for turning said grates in said peripheral bearing relation.

6. In a burner of the character described, the combination of a tubular burner structure mounted approximately on a horizontal axis and including an inner wall surface and means for confining a heat exchange medium in peripheral bearing relation with said wall surface for dissipating heat therefrom, cylindrical grate structures having side surfaces thereof mounted in peripheral bearing relation against said inner wall surface, and means for turning said grates in said peripheral bearing relation, said turning means having a loose connection with the grates for yielding movement of the grates inwardly relative to the wall surface while maintaining the driving connection with the grates.

7. In a burner of the character described, the combination of a burner structure including outer and inner walls spaced apart for confining a cooling medium therebetween in heat exchange relation with the inner wall, said inner wall being substantially cylindrical and having an approxi-

mately horizontal axis, grate-bars mounted in peripheral bearing relation against the inner surface of said inner wall for turning movement in contact therewith throughout a substantial portion of the circumference of said inner wall, said grate-bars extending lengthwise of said inner surface throughout the major portion of the length thereof and movable relative thereto through an orbit for supporting a fuel bed on the grate-bars in the lower portion of the orbit, and means for turning said grate-bars about the axis of said inner wall.

8. In a burner of the character described, the combination of an enclosing structure including an inner wall surface and means for confining a heat exchange medium about said wall surface in heat exchange relation therewith, grate-bars having cylindrical surfaces in peripheral bearing relation against said inner wall surface, rings mounted at opposite ends of the grate-bars and having driving connections therewith, said driving connections being sufficiently loose for inward yielding movement of the grate-bars relative to the rings.

9. In a burner of the character described, the combination of a supporting structure, a plurality of rotating grate-bars adapted for turning movement about an approximately horizontal axis, driving rings having interfitting connections with the grate-bars for rotating said grate-bars in an orbital movement, said interfitting connections being loose relative to the grate-bars for yielding movement of the grate-bars inwardly relative to the rings.

10. In a burner of the character described, the combination of a supporting structure, a plurality of rotating grate-bars adapted for turning movement about an approximately horizontal axis, driving rings having interfitting connections with the grate-bars for rotating said grate-bars in an orbital movement, said interfitting connections being loose relative to the grate-bars for yielding movement of the grate-bars inwardly relative to the rings, and power means having peripheral driving connections at diametrically opposite sides of said driving rings for turning said rings.

11. In a burner of the character described, the combination of an inner wall, grates mounted for rotating movement in peripheral bearing relation with said wall, turning means operatively connected with the grates for rotating said grates through an orbit, and means for applying power equally at approximately diametrically opposite points to the turning means causing movement of said turning means and the grates.

12. In a burner of the character described, the combination of a plurality of grate members, and means mounting said grate members for turning movement through a non-circular orbit, said grate members being constructed for supporting a fuel bed thereon with the orbit.

13. In a burner of the character described, the combination of an enclosing structure, grates mounted within the enclosing structure and constructed of sections spaced lengthwise of said structure, each of said grate sections including a plurality of bars spaced about the circumference of the enclosing structure, and one or more driving rings for each grate section and having interfitting driving connection with the grate-bars to move said grate-bars through an orbit upon rotation of said ring.

14. In a burner of the character described, the combination of an enclosing structure, grates mounted within the enclosing structure and con-

structed of sections spaced lengthwise of said structure, each of said grate sections including a plurality of bar spaced about the circumference of the enclosing structure, and one or more driving rings for each grate section and having interfitting driving connection with the grate-bars to move said grate-bars through an orbit upon rotation of said ring, and means having driving connections with the respective rings for rotating the grate sections.

15. In a burner of the character described, the combination of an enclosing structure, grates mounted within the enclosing structure and constructed of sections spaced lengthwise of said structure, each of said grate sections including a plurality of bar spaced about the circumference of the enclosing structure, and one or more driving rings for each grate section and having interfitting driving connection with the grate-bars to move said grate-bars through an orbit upon rotation of said ring, ash-receiving means beneath the rings, and means for removing ashes from said ash-receiving means.

16. In a burner of the character described, the combination of a tubular structure, a plurality of grates, means mounting said grates for turning movement through an orbit relative to the supporting structure, said mounting means supporting the grates in spaced relation and free for bodily shifting movement relative to each other during movement through the orbit, and means for admitting air to support combustion through the spaces between the grates.

17. In a burner of the character described, the combination of an approximately horizontal tubular structure adapted to support a fuel bed in the lower portion thereof, grates mounted in the tubular structure for bodily turning movement through an orbit relative thereto, and a fire baffle mounted in the supporting structure inwardly of at least a portion of the orbit of movement of the grates to shield the grates from the heat of combustion in the burner during a portion of their rotation.

18. In a burner of the character described, the combination of a plurality of grate members, means mounting said grate members for turning movement through a non-circular orbit, said grate members being constructed for supporting a fuel bed thereon within the orbit, and means for feeding solid fuel to said fuel bed at the inner side of the orbit.

19. In a burner of the character described, the

combination of an annular structure extending about an approximately horizontal axis and including an inner surface and having means for circulating a cooling medium in heat exchange relation with said inner surface, movable grates extending lengthwise of the axis of said annular structure throughout the major portion of the length thereof and mounted for movement through an orbit for supporting a fuel bed on the grates in the lower portion of the orbit, and means for moving said grates in bearing relation with said inner surface.

WESTON M. FULTON.
